(57) **CLAIM**

The ornamental design for a portable folding stand for watercraft, as shown and described.

DESCRIPTION

FIG. 1 is a perspective view of a portable folding stand for watercraft according to an embodiment of the design; shown in use.

FIG. 2 is a front view of the portable folding stand for watercraft.

FIG. 3 is a first side view, the second side being a mirror image thereof.

FIG. 4 is a top view thereof.

FIG. 5 is a bottom view thereof.

FIG. 6 is a perspective view of a portable folding stand for watercraft according to another embodiment of the design; shown in use.

FIG. 7 is a front view of the portable folding stand for watercraft.

FIG. 8 is a first side view, the second side being a mirror image thereof.

FIG. 9 is a top view thereof.

FIG. 10 is a bottom view thereof.

FIG. 11 is a perspective view of a portable folding stand for watercraft according to another embodiment of the design; shown in use.

FIG. 12 is a front view of the portable folding stand for watercraft.

FIG. 13 is a first side view, the second side being a mirror image thereof.

FIG. 14 is a top view thereof; and,

FIG. 15 is a bottom view thereof.

The broken lines are for the purpose of illustrating portions of the portable folding stand for watercraft and forms no part of the claimed design.

1 Claim, 6 Drawing Sheets
